UNITED STATES PATENT OFFICE.

EDWARD W. MILLER, OF SPRINGFIELD, VERMONT, ASSIGNOR TO THE FELLOWS GEAR SHAPER COMPANY, OF SPRINGFIELD, VERMONT, A CORPORATION OF VERMONT.

MACHINE FOR GENERATING AND CUTTING THREADS AND THE LIKE.

Application filed November 15, 1921. Serial No. 515,291.

To all whom it may concern:

Be it known that I, EDWARD W. MILLER, a citizen of the United States, residing at Springfield, in the county of Windsor and 5 State of Vermont, have invented new and useful Improvements in Machines for Generating and Cutting Threads and the like, of which the following is a specification.

The present invention relates to generating and cutting machines.

Its object is to produce a machine of this nature capable of generating and cutting in a continuous operation threads in worms, hobs, taps and the like.

15 A further object is to provide such a machine with such capabilities of adjustment and substitution of different cutting tools for one another that by selection of an appropriate cutter and proper adjustment of the 20 relative generating travel between the cutter and work, threads of any desired pitch and profile, and other work pieces of various undulatory forms of profile, may be produced, within practicable limits as determined by the size and other conditions of the 25 machine. The term "undulatory" as used in this specification in connection with profile work pieces is intended to include any outline consisting of one or more rises and 30 depressions. Within this definition the profile of the thread of any shape is an undulatory line.

Still another object is to combine with 35 means for producing the effects above referred to means for causing the cutter to cut the work piece in such a way as to back off or relieve those parts of the work piece which ultimately become cutting teeth when the work piece is a cutter as a hob, a tap, 40 or cutter of specifically different form.

The manner in which these objects are 45 accomplished and the principles of the invention for which I claim protection herein are explained with reference to a specific machine which is described in detail in the following specification and illustrated in the drawings forming a part thereof. In said drawings,—

Figure 1 is a front elevation of the machine referred to.

Figure 2 is a plan view of the machine.

Figure 3 is an elevation of the left hand end of the machine.

Figure 4 is a right hand end elevation.

55 Figure 5 is a horizontal section, the plane

of which is indicated by the line 5—5 of Figure 4.

Figures 6 and 7 are vertical longitudinal sectional views taken on planes indicated respectively by line 6—6 of Figure 3 and line 7—7 of Figure 4. These two figures together show substantially the entire machine in longitudinal section.

Figure 8 is a cross section on the line 8—8 of Figure 1.

60 Figure 9 is a longitudinal section of the cutter carriage, the plane of which section is indicated by line 9—9 of Figure 10.

Figure 10 is a cross section of the cutter carriage showing the oscillating head partly 70 in elevation and partly in section.

Figure 11 is a sectional view enlarged showing the parts cut by the line 11—11 in Figure 1.

Figure 12 is a vertical section on line 12—12 of Figure 11.

Figure 13 is a horizontal section on line 13—13 of Figure 12.

Figure 14 is a rear elevation of the right hand end of the machine.

Figure 15 is a fragmentary view showing a part of the right hand end of the machine in elevation on a larger scale than Figure 4.

Figure 16 is a detail view partly in section and partly in elevation of the mechanism by which the cutter is caused to take a second or finishing cut.

Figure 17 is a plan view of a part of this mechanism.

Figure 18 is a detail sectional view taken 90 on line 18—18 of Figure 17.

Figure 19 is a cross section showing the adjusting means for regulating the depth of cut and the means for setting the cutter to take a finishing cut.

Figures 20 and 21 are respectively a front elevation and a plan view of a part of the left hand end of the machine equipped with means for generating relief in the work piece, when such piece is a cutting tool such as a hob or the like.

Figure 22 is a partial cross section and partial elevation of the form shown in Figures 20 and 21.

Figures 23 and 24 are diagrams illustrating the gear trains, which are provided at the right hand end of the machine and are shown in Figure 3, as being set to drive the work spindle and feed screw in opposite directions.

Figure 25 is a diagram of the driving and feeding mechanism of the machine resolved into one plane.

Figures 26 and 27 are detail views showing in end elevation and front elevation, respectively, the relation of the cutter to the work.

Like reference characters designate the same parts wherever they occur in all the figures.

A machine embodying the present invention obtains the result of generating desired forms in a thread, or equivalent character of work, by causing not only a feed to take place between the work piece and the cutter at a rate corresponding to the pitch of the thread being cut, but also by causing a rolling motion of the cutter and work, one relatively to the other, which is like the rolling motion occurring between conjugate or complementary gear elements similar in contour to the cutter and work respectively. The cutting edge of the cutter then has an outline similar to the tooth forms of a gear conjugate to the longitudinal section of the work. For instance, a worm having a straight sided thread is in longitudinal section similar to a rack of which the sides of the teeth are straight, and for cutting such a thread the cutter used has the form of an involute spur gear at its cutting edges. For generating threads with other than straight sides, the curves of the teeth on the cutter are otherwise formed conjugate to the desired thread shape. In other respects the cutter is formed according to approved shop practice to have sufficient strength and to make contact with the work only at its cutting edges. Usually the cutter teeth will be helical elements corresponding to the helix angle of the thread being produced, but they need not always have this form, especially in cases where the thread angle being produced is small.

In the particular embodiment of the invention herein illustrated and described, the machine is shown as equipped for cutting a straight sided thread of steep pitch, and the cutter illustrated is one in which the teeth are helically arranged and have the outline of involute spur gear teeth at their cutting ends, being properly relieved from the cutting edges to give proper clearance.

In the drawings the work piece is designated by the numeral 1 and the cutter by the numeral 2. The work is shown in Figure 5 as being carried by a mandrel 3 supported at its opposite ends by a headstock 4 and tailstock 5; that end which is supported by the headstock being connected with a work spindle 6 in any approved way so that it may be rotated by said shaft.

The cutter is secured to the end of the cutter spindle 7, (see particularly Figure 8), which is mounted rotatably in a head 9 car-

ried by a slide 10. The slide is adapted to move endwise on guideways 11 and 12 on the fixed machine base 13. The head and slide together form the cutter carriage, and the direction in which such carriage is able to move is determined by the guideway 11, which is formed as a rib embraced between a shoulder 14 and an adjustable gib 15 on the carriage.

Driving and feeding mechanism.—In this particular machine the cutter acts on the upper side of the work and the latter is rotated so that its upper side turns toward the cutter. The cutter carriage travels from left to right and the cutter is at the same time rotated in counter-clockwise rotation as viewed from the front of the machine; that is, when cutting right hand threads. Attention is directed to Figures 1 to 8 inclusive and the diagram Figures 23, 24, and 25 for illustration of the gearing applied for this purpose. The cutter carriage is moved endwise by a lead screw 16, and the cutter is rotated by a long worm 17 in mesh with a worm wheel 18 which is engaged with the cutter spindle 7 through the medium of a sleeve 19 (Figure 8), on the outside of which the worm wheel is mounted and connected by a key 20, and inside of which the spindle has a splined engagement by means of a feather 21. This lead screw, this worm, and the work spindle are all rotated by the same pulley 22 which is driven by a belt. 23 is a loose pulley beside the pulley 22 adapted to receive the belt when the machine is idle. Pulley 22 is connected with a sleeve 24 (Fig. 6) which surrounds the shaft extension 17a of the worm 17 and has a splined engagement therewith by means of a key or feather 26. Thus the worm is rotated by means which permits of an endwise movement being given to the worm at the same time. The gear 27 is keyed on the sleeve 24 and drives the work spindle 6 through the drive gears 28 and 29 and change gears 30 and 31 (see Figures 3, 23, 24, and 25). The proper ratio of rotation between the cutter and the work is determined in accordance with the number of teeth in the cutter and number of threads to be produced in the work, and also the number of teeth in the worm wheel 18 and threads in the worm 17, by applying change gears 30 and 31 of the proper ratio.

The lead screw 16 is driven by an extension of the same gear train consisting of a gear 32 on the work spindle, a gear 33 (in mesh with 32) and a connected pinion 34, on an intermediate stud 35; a gear 36 in mesh with 34 and keyed to a short shaft 37, a shaft 38, and a pair of change gears 39 and 40 on the shaft 38 and lead screw 16, respectively. A reversing gear mechanism is interposed between the shafts 37 and 38 in order that the direction of rotation of the lead screw may be reversed and the carriage

5 returned to its starting point, without reversing the other mechanism. This reversing gear consists of a bevel gear 41 fast to shaft 37, a bevel gear 42 loose on the shaft 38, an intermediate bevel gear 43 in mesh with both 41 and 42, and a double ended clutch sleeve 44 adapted to be moved by a clutch shifter 45 into connection either with a complementary clutch on the gear 41 or 10 with another complementary clutch on the gear 42; said clutch sleeve being splined to the shaft 38.

Both the work spindle and lead screw may be driven in the reverse direction to cut left hand threads in the work by shifting the gear 28 of the train previously described into mesh with the reversely rotating gear wheel 46, which is mounted on a stud 47, in mesh with the gear 27 and continuously rotated thereby. In order that gear 28 may be thus shifted it is mounted eccentrically on a shaft 48 (Figures 23 and 24) which is adapted to be oscillated in its fixed bearings by a crank 49 (Figures 1 and 2) having a locking pin 50. The change gear 30 and its associated gear 29 are mounted upon a quadrant 51 (Figure 3) which is adapted to swing about that zone of shaft 48 which is concentric with gear 28, and is secured by a clamp screw 52.

The entire gear train 27—36 is mounted at the left hand end of the machine in a casing 53 having a detachable cover; and the change gears 39 and 40 are mounted at the right hand end of the machine in a casing 54 also having a detachable cover, whereby said gears are accessible.

Although the worm 17 has an endwise movement as well as a rotational movement, for a purpose which is later described, yet this endwise movement takes place otherwise than in unison with the feed movement of the cutter carriage. Thus a relative motion in the line of feed occurs between the carriage and the worm, which transmits to the cutter a further degree of rotation beyond that due to the rotational movement of the worm. Rotation of the worm alone (the feed movement of the carriage being disregarded) gives to the cutter the same character of rotation as that of a worm wheel turning on a stationary axis in mesh with a rotating and otherwise stationary worm of the same pitch as the work. The rotation of the cutter, due to the endwise relative motion between carriage and worm, compounded with its displacement bodily due to the travel of the carriage (rotation of the worm being now disregarded), causes the cutter to roll along the work in the same manner as a pinion having the same form as the cutter would roll in mesh with a stationary rack having teeth conjugate to those of such pinion. The resultant motion which actually takes place (with respect to the cut-

ter and work piece) is compounded of all the single motions just described, and enables the cutter to cut a thread of full required depth in one pass across the work. The amount of stock removed by each cutter tooth is determined by the speed of carriage travel, and may be regulated as required by proper selection of the change gear pair 39-40. That component of the cutter rotation due to the rotation only of the worm causes the cut made to be helical; while the additional rotation, and translative movement, of the cutter due to relative endwise travel of carriage to worm causes the operation to progress along the work and the sides of the thread to be generated truly conjugate to the tooth curves of the cutter. This last mentioned component of the cutter movement may be called the "generative travel" of the cutter.

Compensation for difference in diameter of cutter and driving worm wheel.—Preferably the worm wheel 18 which drives the cutter rotatably is larger in diameter on its pitch circle than is the cutter, from which it follows that if the worm 17 had no endwise movement the cutter would destroy the work on account of its generative travel being slower than the displacement travel of the carriage. Therefore the worm is moved endwise oppositely to the movement of the carriage whenever the latter is set in motion. To obtain this result a rack 55 is mounted at the rear of the machine (Figures 2, 3, 4, 14, 15, and 25) in a fixed guide 56 and is connected with the carriage slide by means of a tongue 57 secured to the slide and entering a notch in the rack. The teeth of this rack mesh with a gear wheel 58 secured to a transverse shaft 59, on which there is also secured a gear 60, which is one of a pair of change gears. The other change gear 61 of this pair is mounted on a shaft 62 which crosses from one side to the other of the machine and carries on its other end a gear 621 meshing with a gear 63 on a shaft 64. Gears 621 and 63 are also change gears. Shaft 64 carries a gear 65 in mesh with a rack 66 which is formed on a sleeve 67 surrounding the extremity 17^b of the worm shaft and in which the latter has a rotative bearing. This rack sleeve 67 is retained in position by a thrust shoe 68 fastened to the rigid casing at the end of the machine in a manner such that the rack sleeve may be moved endwise through it. By proper selection of the change gears 60—61 and 621—63 such endwise movement may be given to the worm during the travel of the cutter carriage as will make the generative travel of the cutter the same as the travel of a pinion having the same pitch diameter on a stationary rack of the same pitch as the thread being cut in the work.

Adjustment of cutter.—The cutter is ad. 130

justable angularly about the axis of the worm 17 in order that it may cut to the proper depth in work pieces of different diameters; and it is also adjustable in the direction of its axis to bring the plane of its end face, in which the cutting edges lie, radial to the work piece, or in such other predetermined position as may carry out the best practice in cutting. The worm wheel 18 is also adjustable in and out with respect to the worm 17 in order to take up looseness and obtain its proper mesh with the worm. For an explanation of these adjustments attention is called to Figures 6 to 10 inclusive. The cutter head 9 is provided with hollow trunnions 69 and 70 which occupy bearings 71, 72 in the slide 10 and are retained by bearing caps 73 and 74. These trunnions are coaxial with the worm 17 and furnish the bearings in which the latter turns. Thus the cutter head is able to oscillate about the worm and the distance of the cutter from the axis of the work spindle is changed by so doing. In order to set the cutter at a given distance from this axis, there is provided a bar 75 (Fig. 19) which is movable endwise in a guideway 76 in the cutter head and carries an anti-friction roll 77 which makes contact with an abutment or stop 78, such stop having in this machine the form of a cam whereby it performs an additional function presently described. The bar or slide 75 is threaded and meshes with internal threads in a sleeve nut 79 on which is fastened a wheel 80 for rotation manually. This sleeve nut is held in place by a bearing sleeve 81 which is secured within the guideway. A plunger 82 (Fig. 10) confined and movable endwise in a second guideway 83 is pressed by a spring 84 toward a stationary abutment 85 on the slide, and serves to hold the roll 77 against the abutment 78 and to maintain the cutter in its operative relation to the work. Adjustment of the cutter head around the axis of the worm changes the angle which the cutting face of the cutter makes with the nearest radius of the work spindle. Endwise adjustment of the cutter spindle to bring the cutter plane radial to the work is accomplished by rotation of a stem 86 which is threaded at its inner end and is screwed into a complementary threaded socket 87 in the end of the spindle. This stem is rotated by an external head 88 and is retained against endwise movement by a nut 89 which is screwed upon the end of the bearing sleeve 19 and has a lip which confines a shoulder 90 of the stem against the end of this sleeve. The sleeve meanwhile is prevented from moving endwise by means of a nut 91 threaded upon its exterior and abutting against a collar 92 which abuts against the bearing 93, the latter being restrained by the cap 94 of the head, and a washer 95 and ring 96.

When any adjustment has been given to the cutter spindle 7 in the manner described, such adjustment is locked by expanding the split end of the threaded stem 86 against the walls of socket 87 by means of an expanding plug 97 on the inner end of a rod 98 on which is a nut 99 abutting against the end of the stem. The key or feather 21 between the cutter spindle and bearing sleeve permits such endwise adjustment of the spindle as may be required, without destroying the rotation-transmitting connection between the spindle and its driving worm wheel.

To obtain an exact adjustment of the penetration and closeness of fit between the threads of worm 17 and the teeth of wheel 18, the wheel and bearing sleeve 19 are mounted eccentrically in a tubular holder 100 which is rotatable within the cutter head 9. This holder has teeth on a part of its exterior as indicated at 101 in Figure 9, and engaged with these teeth is an adjusting worm 102 of which the shank 103 protrudes from the cutter head and is adapted to be engaged and turned by a wrench.

Finishing cut feed.—Although a thread may be cut to full depth in one pass, nevertheless it is preferred, in the interest of accuracy and smooth finish, to cut the thread nearly but not quite to its final width and depth in the first pass of the cutter over the work, and then to reduce it to finished size by a light cut taken in the reverse travel of the cutter. The abutment cam 78 (Figs. 16-19) cooperates with other mechanisms presently described in feeding the cutter to the proper depth for the finishing cut. This cam then has a single step 104 and is circular at each side of the step. When the operation on a work piece is started, the cam occupies the position where the high part on one side of the step is in contact with roll 77, and the adjuster 75 is so set that the preliminary or roughing cut will be less deep by an amount equal to the height of the cam step 104 than that needed for the finished work. Cam 78 is mounted on a shaft 105 which is rotatable in bearings in the carriage slide 10 and is held so as to move endwise with the latter. It is additionally supported by a bearing 106 in the stationary frame (Fig. 17) with respect to which it is both rotatable and endwise movable. A collar 107 is mounted on this shaft and carries a projection 108 adapted to be acted on by two stationary abutments 109 and 110, respectively, on a bracket 111 which is secured to the machine frame. When the cutter carriage reaches the end of the first traverse, the projection 108 engages the abutment 109 and is thereby so displaced that the high part of the cam 78 is moved away from the roll 77 and the low part of the cam brought into position. Thus the cutter is automatically fed into the work,

and upon the return travel of the carriage is enabled to make a light finishing cut. At the end of the return traverse the projection 108 is so displaced by the abutment 110 as to return the cam to previous position. The cam thus described is equivalent to, and typifies any sort of cam or wedge device which might be used for the same purpose, whether oscillatable about an axis as shown, 10 or arranged and movable in any other manner.

Cutter carriage reversing mechanism.—The automatic return of the carriage after completion of the first cut is effected automatically by shifting of the clutch 44 from engagement with the gear 41 into engagement with the gear 42, whereby the direction of rotation of the lead screw 16 is reversed. The clutch shifter 45 is moved to that effect by mechanism shown in Figures 1, 5, 11, 12, and 13. This clutch shifter is pivoted on a stud 112 fixed on a bracket 113 (Figure 11) and has an arm 114 coupled by a pin and slot connection with a block 115 which slides on a bar 116 fixed in a housing 117 secured to the frame of the machine. In the housing is mounted a rock shaft 118 carrying an arm 119 on which is fixed a stud 120 and to the opposite sides 25 of which are pivoted swinging arms 121, 122, each also connected to said arm by a spring 123. The stud 120 projects between two dogs 124 and 125 which are pivoted in the housing 117 at opposite sides of the sliding block 115. The swinging arms are also pressed by the springs 123 against opposite sides of another part of this block. The dog 124 has one locking abutment 126 and the dog 125 has two such abutments, 127 and 30 128. Figure 12 shows this mechanism in the neutral position, wherein the abutment 128 engages the block and abutment 126 rests on the block. If now the arm 119 should be moved to the right for instance, the stud 120, bearing on an inclined surface 129 of the dog 125 would raise the latter so as to clear the abutment 128 of the block, and the spring pressed arm 122 would then be free to move the block to the right, which would 35 result in coupling the clutch 44 with the gear 41, the condition required for the first traverse of the machine. The dog 124 then falls so as to lock the slide in this position by means of abutment 126. If now the arm 119 is moved in the opposite direction the dog 124 is first released from the slide, and then the latter is moved by the spring pressed arm 122 to shift the clutch into reverse driving position, and it is locked in 40 this position by the shoulder 127.

A handle 130 is made fast to the rock shaft 118, by which the movements of the arm 119 just described may be carried out manually; and there is also secured to the rock shaft, as part of the arm 119, a forked

arm 131, the fingers of which embrace stud 132 on an endwise movable bar 133. This bar carries separate trip pins 134 between which are trip dogs 135 on the carriage slide. There are two of such dogs seated 70 in a groove 136 on the edge of the slide and thereby adapted for adjustment to determine the times at which automatic reversal and arrest of the carriage will take place.

It will now be understood that if the carriage is set in motion by that movement of the handle 130 which moves the arm 119 to the right from the neutral position shown in Figure 12, the carriage will be fed from left to right until the right hand trip dog strikes the right hand trip pin. Then bar 133 will be moved to the right, arm 119 is moved to the left, and the feed control clutch moved to the right with the effect of reversing the direction of carriage travel. On return to the starting position, the left hand trip dog strikes the left hand trip pin and causes the control switch to be shifted into neutral position, because as soon as the locking shoulder 127 has been disengaged from the slide 115 the latter is moved by the spring arm 121 only to the point at which it is arrested by shoulder 128, which point is in the neutral position.

Operation.—It may be assumed first that the machine is prepared for cutting a thread of a certain pitch in a work piece of a certain diameter by the application of the cutter and change gears appropriate to the particular case. If the feed controlling 100 clutch 44 is in the neutral position, starting the machine by shifting the driving belt over to the fast pulley 22 will simply cause the cutter and the work piece to rotate at their appropriate speeds. With the carriage located at the left hand end of its travel and clear of the work piece, the high part of cam 78 will be in position to gauge the depth of the cut. Adjustment of the cutter by means of the wheel 80 and head 88 will already have placed it in position to take a roughing cut of predetermined depth. Now if the control handle 130 is shifted to the left the reversing clutch is 105 coupled with the gear 41 and the feed mechanism is driven in the directions indicated by the arrows on Figure 25 to shift the carriage slowly toward the right. Thus the cutter is carried along the work and its rotation in the counter-clockwise direction 110 is at the same time made enough less by relative endwise displacement of the carriage and worm 17 than that due solely to the rotation of the worm, that a slow rolling effect of the cutter relatively to the work 115 takes place, whereby the thread being cut is extended along the work from the starting point and the sides of the thread are generated to the form determined by the edge 120 outlines of the cutter teeth. Arrived at the 125

end of the feed movement (the limits of which are variable by adjustment of the right hand trip dog 135), the clutch is shifted so as to cause reversal of the carriage feed, and at the same time the cam 78 is so turned by contact of the roll 108 with the wedging abutment 109 that its low part comes into contact with the stop roll 77 and the cutter is fed enough further into the 10 work to take a finishing cut. It may be noted here that the abutments 109 and 110 are adjustable longitudinally in the bracket 111, whereby they may be placed to bring the finishing cut feed into proper time with 15 the reversal of the longitudinal feed.

When this reversal occurs the feed screw is turned in the opposite direction and the cutter is returned from right to left, the cutter driving worm then being moved from 20 left to right, and the cutter being given a higher rate of rotation than that due solely to the rotation of this worm. The increase in the cutter rotation now caused by left hand traverse of the carriage and right hand 25 traverse of the worm is equal to the decrease in the rate of cutter rotation following from endwise movements of the carriage and worm in the opposite direction during the roughing cut feed, whereby the 30 equivalent character of rolling generative travel of the cutter relatively to the work is given during the finishing cut as during the roughing cut. When the carriage reaches its original starting point the clutch shifter 35 mechanism is tripped by the left hand trip dog 135 and reversing clutch returned to the neutral position, whereby the carriage comes to rest. Automatic means may be provided for stopping the entire machine 40 by shifting the driving belt off the fast pulley at this time, if desired, but such means are not part of the present invention and are, therefore, not shown herein.

Further uses of the invention.—Modifications in the machine thus particularly described may be made, by way of additions or eliminations or changes in structure or arrangement of the several elements of the machine, within the fundamental principles 50 of the invention and within the scope for which I claim protection. One possible modification for a specific purpose is illustrated in Figures 20 to 22, where the machine is shown prepared for making cutters 55 such as hobs, taps and other formed cutters which are capable of being generated. Such cutters are notched or gashed to provide cutting teeth. For making such work pieces the teeth produced between the 60 gashes or notches must be backed off or relieved from those ends thereof where the cutting edges are formed to give the clearance necessary in cutting tools. Such 65 backing off is effected by a modification of the depth feed cam 78 and of the means for

driving it. This modified cam is shown at 78^a, in Figures 20 and 22 and represented as having a number of similar lobes and of being driven at a predetermined rate of rotation from the work spindle 6 by means of intermeshing gears 138 and 139 on the work spindle 6 and the cam shaft 105 respectively.

Assuming that the work piece 1^a in this case is a hob having eight teeth, then the 75 number of lobes in the cam and the gear ratio 138 to 139 are such as to cause eight rises and descents of the cutter during each rotation of the work piece. The rises and descents of the cam are so formed and arranged that the cutter is withdrawn from the axis of the work while in the open spaces or gashes of the work piece and is gradually advanced toward such axis while acting on those parts of the work which eventually 80 become teeth. In order that generative travel of the cutter may take place together with continuous rotation of the relieving cam when the work piece is to be itself a generated cutting tool, the gear 139 is preferably splined to the shaft 105 and is restrained from endwise movement by a bracket 140; or other well known mechanical expedients for obtaining the same effect 85 may be used. Other specific uses of the machine for turning out work of the same general character and in essentially the same way as herein described, although specifically different in detail, are within the scope 90 of my contemplation and are intended to 95 be protected by the appended claims.

For the purpose of this specification work pieces of all characters capable of being produced by this machine may be considered as formed with a rib or ribs surrounding the axis of revolution of the piece. In the case of a worm or other piece having a thread, whether continuous or interrupted, each turn or section of the thread is ribbed within this definition. Ribs of non-helical 100 character or of zero thread angle may be generated in this machine by omitting the rotary movement of the worm 17, as by removing the connection between this worm and its driving pulley, or in place of the 105 worm a cylindrical rack may be substituted. In that case the generative travel of the cutter relatively to the work is the same as already described, but the cutter is not given that increment of rotation which 110 causes the generated rib to be helical. Other work pieces with non-helical ribs of many 115 diverse shapes in profile may be generated by essentially the same machine and in the same manner as described, with the use of 120 appropriate cutters.

What I claim and desire to secure by Letters Patent is:

1. A thread generating machine comprising a cutter holder, a cutter rotatably 130

- mounted upon said holder and having a dentate cutting edge similar in outline to a gear wheel, means for supporting a substantially cylindrical work piece and rotating said work piece about its geometric axis, means for effecting relative displacement between the cutter holder and work piece in the direction of the axis of the latter, and means for rotating the cutter consisting of a worm wheel rigidly connected with the cutter but of different pitch diameters and a rotatable worm in mesh with said worm wheel, the worm being at the same time displaced endwise relatively to the cutter holder at such a rate that the cutter is caused both to rotate in the manner of a worm wheel in mesh with a worm corresponding to the work piece and to roll relatively to the work piece in the manner of a gear wheel rolling in mesh with a rack.
2. A thread generating and cutting machine comprising means for supporting a substantially cylindrical work piece and rotating said piece about its geometric axis, a cutter carriage, means for effecting relative movement between the carriage and work-piece in a path approximately parallel with the axis of the work piece, a cutter spindle rotatably mounted in said carriage with its axis transverse to that of the work piece, a dentate cutter applied to said spindle and having peripheral teeth similar in outline to those of a gear element adapted to mesh with the thread to be cut, and means for rotating said cutter spindle comprising a worm wheel attached to the spindle, a worm arranged parallel to the path of movement of said carriage, means for rotating the worm about its axis and means for causing at the same time relative endwise movement to occur between the carriage and the worm, of different amount than the movement between the carriage and work-piece.
3. A thread generating machine comprising a carriage or holder for a cutter, a cutter spindle rotatably mounted upon said carriage or holder, a dentate cutter similar in outline at its cutting edge to a gear wheel applied to said spindle, a worm wheel of different diameter than the cutter affixed to said spindle, a worm passing through said holder in mesh with said worm wheel, supporting and rotating means for a work piece adapted to rotate the work with its surface in contact with the cutter, mechanism for rotating the worm and the work piece at such rates of rotation in proportion to the pitch of the worm and of the thread to be cut and to the number of teeth in the worm wheel and cutter, respectively, that said cutter is caused to rotate along the work in the manner of a worm wheel running in mesh with a worm similar to the thread being cut, and means for also producing such relative endwise movement between the holder and work piece and a different extent of similar movement between the holder and worm that a component of motion is given to the cutter relatively to the work like that of a gear wheel rolling in mesh with a rack.
4. A thread generating and cutting machine comprising a cutter holder, work holding means adapted to support and rotate a work piece, a cutter spindle rotatably held by said holder with its axis transverse to that of the work piece, a dentate cutter having its cutting edge similar to the teeth of a gear adapted to mesh with the thread designed to be cut, said cutter being applied to said spindle and arranged to engage the surface of the rotating work, a worm wheel secured to said spindle and being of a diameter greater than that of the cutter, a worm arranged in mesh with said worm wheel and being movable endwise, mechanism for simultaneously rotating the work piece and worm at such rates of speed that the cutter is caused to rotate with a linear speed equal to the pitch displacement of the thread being cut, and means for effecting relative displacement of the work piece and the cutter holder lengthwise of the work piece and relative displacement between the said holder and the worm longitudinally of the worm at such rates that a component of motion relatively to the work is imposed on the cutter like that of a spur gear rolling in mesh with a rack.
5. In a thread generating machine, a traveling cutter carriage, a cutter spindle rotatably mounted in said carriage, a dentate cutter affixed to said spindle, a worm wheel of greater diameter than the cutter also affixed to said spindle for rotating it, a worm in mesh with said worm wheel for driving the latter and arranged with its axis parallel to the direction of travel of the cutter, and mechanism for shifting the worm endwise oppositely to the movement of the carriage at a rate proportional to the difference between the diameter of the worm wheel and the diameter of the cutter.
6. In a thread generating machine a movable cutter carriage, a cutter spindle rotatably mounted in said carriage, a worm wheel secured to said spindle, a worm in mesh with said worm wheel and arranged with its axis parallel to the path of the carriage, a rack connected to and movable with the carriage, and transmission gearing driven by said rack and arranged to transmit movement endwise to the worm when the carriage is in motion.
7. In a thread generating machine, the combination with a work support and means for rotating a work piece, of a cutter carriage movable along the surface of the work piece, a rotatable dentate cutter carried by

said cutter carriage, means for giving to said cutter a resultant motion of rotation relative to the work which is compounded of the motions of a worm wheel running in mesh with a worm similar to the completed work and of a gear in mesh with a rack, reversible longitudinal feed mechanism for the carriage, a depth feed abutment for the cutter, and mechanism for reversing the longitudinal feed mechanism and giving an additional amount of depth feed to the cutter at the end of the travel movement of the cutter along the work.

8. In a thread generating machine, the combination with a work support and means for rotating a work piece, of a cutter carriage movable along the surface of the work piece, a rotatable dentate cutter carried by said cutter carriage, means for giving to said cutter a resultant motion of rotation relative to the work which is compounded of the motions of a worm wheel running in mesh with a worm similar to the completed work and of a gear in mesh with a rack, reversible longitudinal feed mechanism for the carriage, a depth feed abutment for the cutter, mechanism for reversing the longitudinal feed mechanism, and means for so shifting said abutment as to give an additional amount of depth feed to the cutter at the end of the travel movement of the cutter along the work.

9. In a generating and cutting machine comprising a work holder adapted to support and rotate a work piece, a cutter holder, a cutter carried rotatably by said holder, means for effecting translatable displacement between the cutter holder and work holder, a worm wheel of larger diameter than the cutter connected thereto, a rotatable worm meshing with said worm wheel, means for giving such movements to the worm compensating for the larger diameter of the worm wheel, that the cutter is caused to roll along the work for generating a given form, said cutter being movable toward and away from the work for regulating the depth of cut, a stop formed as a cam arranged to act on the cutter holder for limiting the depth of cut, and means for shifting said cam during the operation of the machine and thereby altering the depth of cut.

10. A generating and cutting machine comprising a work support and work rotating means, a cutter spindle, a holder upon which said spindle is mounted rotatably, a cutter similar to a gear wheel on said spindle coaxial therewith and located in position to act upon the work, a toothed wheel of larger pitch diameter than said cutter secured to said spindle, a ribbed gear element in mesh with said toothed wheel, means for effecting simultaneous relative movement between the cutter holder and the work and between the cutter holder and said ribbed element in

such directions and at such rates of speed that the cutter is given a rolling movement with relation to the work like the rolling movement of a pinion in relation to a rack with which it is in mesh, the cutter holder being otherwise movable to shift the cutter toward and away from the axis of the work, and means for so moving the holder during the operation of the machine.

11. A generating and cutting machine comprising work holding means, a work rotating spindle, a carriage movable approximately parallel to the axis of rotation of the work, a cutter spindle rotatably mounted on said carriage and extending transversely to the work piece, a dentate cutter mounted on said cutter spindle and having its cutting edges in a plane perpendicular to said spindle, a toothed wheel fast to the cutter spindle, an elongated ribbed gear element in mesh with said toothed wheel, means for moving the carriage lengthwise of the work, and means for effecting such endwise movement of said ribbed element, different from that of the carriage, that the movement of translation of the carriage relatively to the work and to said ribbed element causes a rolling movement of the cutter similar to that of a gear rolling in mesh with a rack.

12. In a generating and cutting machine, a cutter carriage comprising a base, a head oscillatively mounted on said base, a cutter spindle rotatably mounted in said head, a dentate cutter and a toothed wheel larger than said cutter connected with said spindle, a ribbed gear element of circular cross section in mesh with the teeth of said wheel located with its axis of curvature in the axis of oscillation of the head, means for effecting a relative longitudinal movement of displacement between the head and said ribbed element and means for giving an additional component of motion to said ribbed element in compensation for the larger diameter of said toothed wheel whereby to cause rolling movement of the cutter on its pitch circle.

13. In a generating and cutting machine, a cutter carriage comprising a base, a head oscillatively mounted on said base, a cutter spindle mounted rotatably and movable endwise in the head, an elongated gear element circular in cross section arranged with its axis approximately coincident with the axis of oscillation of the head, and having surrounding ribs, a toothed wheel in mesh with the ribs of said gear element having a splined connection with the spindle, and means for adjusting said spindle endwise relatively to the toothed wheel.

14. In a generating and cutting machine, a cutter holding head, an elongated ribbed element, a cutter spindle rotatably mounted in said head, a toothed wheel connected with said spindle and meshing with said elong-

- gated ribbed element, and means for mounting the spindle and toothed wheel with provision for adjustment of the latter toward and away from the elongated ribbed element 5 comprising a holder rotatably mounted in the head and having a bearing for the spindle eccentric to its bearing in the head, whereby rotation of said holder is adapted to shift the spindle and toothed wheel.
- 10 15. In a thread generating and cutting machine, a cutter carriage, a cutter spindle rotatably mounted in said carriage, a worm wheel connected to said spindle for imparting rotation thereto, said carriage including 15 a head oscillatively mounted by which the spindle and worm wheel are held, a worm passing through the axis of oscillation of the head and being in mesh with the worm wheel, means for rotating said worm, and means for giving a relative endwise movement of displacement between the worm and carriage.
16. In a thread generating and cutting machine, a cutter carriage, a cutter spindle rotatably mounted in the carriage, a worm wheel on said spindle, a worm extending past the said worm wheel in mesh therewith and in a direction substantially parallel to the path of movement the carriage, a 25 rack connected with the carriage to be moved thereby and therewith, and gearing driven by said rack and arranged to apply endwise movement to said worm.

In testimony whereof I have affixed my signature.

EDWARD W. MILLER.
